(57) **CLAIM**

The ornamental design for a display screen or portion thereof with graphical user interface for a clamp display of a cardiopulmonary bypass machine system, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface for a clamp display of a cardiopulmonary bypass machine system showing a first embodiment of the new design; and,

FIG. 2 is a front view of a second embodiment thereof. The broken lines immediately adjacent the outer edge perimeter of the graphical user interface shows a display screen, and forms no part of the claimed design. All other broken lines show portions of the graphical user interface and form no part of the claimed design.

1 Claim, 2 Drawing Sheets
